O. MOWERS

PUMP

Filed Oct. 23, 1920

UNITED STATES PATENT OFFICE.

OSMYN MOWERS, OF HOUSTON, TEXAS, ASSIGNOR OF ONE-HALF TO THE GUIBERSON CORPORATION, OF DALLAS, TEXAS, A CORPORATION OF DELAWARE.

PUMP.

Application filed October 23, 1920. Serial No. 418,899.

To all whom it may concern:

Be it known that I, OSMYN MOWERS, a citizen of the United States, residing at Houston, Harris County, Texas, have invented a certain new and useful Improvement in Pumps, of which the following is a full, clear, and exact description, such as will enable others skilled in the art to which it appertains to make and use the same.

10 My invention relates to an improvement in means for pumping oil, water or other fluids from wells of any depth. It is especially adapted for use in the pumping of liquids containing quantities of sand or 15 sediment, which ordinarily tends to wear both the pump barrel and the plunger.

An object of my invention is to provide 20 a device for raising liquids from the well, which, because of its action, will be exposed to a minimum amount of wear and which will work for long periods of time without the necessity of removal of the working parts.

Another object is to provide a device of 25 this character which will operate in the ordinary pump tubing without the necessity of supplying special working barrels in which to operate.

Another object is to provide a pumping 30 device which will automatically clear itself of sand or similar material and thereby avoid clogging of the parts.

Other objects and advantages will appear 35 in the specification which follows and the points of novelty thereof will be referred to with more particularity in the claims.

40 Referring to the drawing herewith, in which like numerals of reference are applied to like parts in both the views, Fig. 1 is a central longitudinal section through a well casing and tubing showing my improved pumping device in operative position therein. Fig. 2 is a central longitudinal section, on an enlarged scale, of one of the cups used with my invention.

45 In the ordinary type of pump employed in pumping wells, it is customary to provide a plunger having a close fit with the working barrel of the pump and it is also customary to provide a special type of working barrel made of hardened metal to withstand the wear occasioned by the reciprocation of the plunger. In the operation of my device, however, I contemplate using the ordinary 50 tubing which forms the upper portion of

the ordinary pump barrel, it not being necessary to provide any special working barrel when my device is employed. In Fig. 1 I have shown a tubing 1, as being inserted downwardly within the casing 2 of a deep 60 well. The tubing 1 is closed at the lower end, there being an opening 3 in the said closure, this opening being normally closed by means of a valve 4 of any ordinary construction, this valve being adapted to open 65 upwardly in the usual manner.

The lifting device employed for raising the fluid within the tubing 1 is of special construction. I contemplate employing a plurality of frusto-conical shaped cups 5, 70 said cups being connected at spaced intervals along an ordinary solid sucker rod 6 of the usual construction. It is possible, of course, in shallow wells to use but one of these cups 5, but in deep wells it will be 75 preferable to use a plurality of them, each cup being spaced from the other by a suitable distance, which may be anywhere from about twenty-five to one hundred feet apart.

In Fig. 2 I have shown a more detailed 80 view of the construction of the cups 5 and of their connection within the operating pump rod. The cup 5 is mounted upon a section of pipe 7, threaded at its lower end 85 at 8 for connection with a length of sucker rod and having the upper portion of the said pipe counterbored for about half its length and threaded interiorly at the upper point 9 thereof for attachment to the adjacent length of sucker rod 10. The cup 5 is 90 secured intermediate the ends of the pipe section 7, the smaller end of the cup being presented downwardly and attached firmly about the pipe 7 and retained in position by means of diametrical rivets 11, or any other 95 preferable means, the object being to hold the cups in fluid-tight relation to the pipe. This cup 5 may be formed of leather, rubber, or any flexible wear-resisting material. The upper and larger end of the cup, in its 100 ordinary position, is slightly smaller in diameter than is the inner diameter of the tubing 1. It is retained in its upright position, so that it may not be forced to double backwardly, by means of a series of connecting braces 12, of which I ordinarily employ four in number. These braces 12 may be made of strips of sheet iron or steel, secured at their upper ends to a sliding collar 13. This collar is limited in its down-

ward movement by means of a ring 14 which is shrunk securely upon the outer surface of the pipe 5 at such a point as to prevent the downward movement of the collar 13 beyond the point where the outer upper edge 15 of the cup contacts with the inner surface of the tubing 1. At the lower end of the counter-bored portion of the pipe 7, I form a seat 16 for a ball valve 17. This seat 16 is intended to be removable and may be made of brass, bronze or any other suitable material.

The pipe 7 is perforated below the cup 5 at 18 to allow the entrance of some of the fluid being pumped into the inner channel of the pipe. Above the valve seat 16, and within the cup 5, are a plurality of openings 19 to allow an outlet for the fluid inside the cup. Above these openings 19 is a cross pin 20 adapted to limit the upward movement of the ball valve 17 in an obvious manner.

The operation of my device is as follows: On the upward stroke of the pump rod, the foot valve 4 at the lower end of the tubing will be raised by the action of the cups 5, drawing into the tubing 1 a charge of fluid. The cups on the upward stroke will be forced outwardly against the inner face of the tubing 1 by the head of fluid already within the tubing. As the outer edge 15 of the cup is thus thrown against the tubing the sliding ring 13 will be drawn downwardly and will contact with and be prevented from further movement by the ring 14. The valve 17 will be held within its seat 16 and the fluid above the cup will be raised within the tubing.

On the downward stroke of the sucker rod, the foot valve 4 will be closed and the fluid within the tubing will be forced upwardly past the cups 5. The cups will hence be contracted so as to allow the passage of water around the outer margin of the cups, the sliding ring 13 will be forced upwardly and the pressure of the water within the tubing will force a flow inwardly through the openings 18 and will raise the valve 17 off its seat and allow the passage of fluid out through the openings 19 and upwardly inside the cup. The parts will then be in the position shown in Fig. 2. This flow of fluid through the pipe 7 will carry any sand or dirt upwardly away from the cup and prevent its lodging therein, thus preventing the clogging of the cup and leaving it free to operate at all times.

The use of a series of these cups along the sucker rod is valuable for the reason that a better lifting action is obtained thereby, and because the head of water standing within the tubing will not all rest upon the lower plunger, as is usually the case. The cup will have to support only the head of water between it and the next upper adja-

cent cup. The wear upon the cups will thus be greatly lessened. It will be noted that the outer edge 15 of the cup will only be in contact with the tubing on its upward stroke and that on its downward stroke the sediment which might tend to collect about the outer edge thereof will be drawn upwardly by the current of fluid. On the upward stroke of the plunger, the sediment will not have an opportunity to collect materially between the cup and the tubing and for this reason the usual amount of wear will be greatly minimized. Wells equipped with this device have been found to operate much longer before repair is necessary than is the case with the usual type of plunger.

Having thus described my invention, what I claim as new and desire to protect by Letters Patent is:

1. In a pump, a pump rod, a tubular pipe section thereon, a flexible cup secured to said section, said pipe section having openings therein above and below the point of attachment of said cup and an upwardly opening valve in said pipe section, said cup being adapted to collapse on the downward stroke of said rod to allow the passage of most of the fluid outside thereof.

2. In a pump, a pump rod, an upwardly flaring cup of flexible material secured tightly to said rod, a sliding ring on said rod above said cup, attaching means between the upper edge of said cup and said ring and means to limit the downward movement of said ring.

3. In a pump, a pump rod, a tubular section connected therein, a frusto-conical, upwardly flaring cup secured intermediate the ends of said section, said section having perforations above and below the point of attachment of said cup, and an upwardly opening valve in said section, there being a sliding engagement between the upper end of said cup and said rod whereby said cup may collapse on the downward stroke.

4. In a pump, a string of tubing, a foot valve at the lower end thereof, a sucker rod, a cup thereon, said cup being normally of less diameter than said tubing, means slideable on said rod to limit the expansion of said cup and means to keep said cup from clogging.

5. In a pump, a string of tubing, a foot valve therein, a cup of flexible material reciprocal above said valve, and means to allow passage of a portion of the fluid being pumped inside said cup to flush it free of sand and sediment, the cup being adapted to collapse to allow most of the fluid to pass outside thereof.

6. In a pump, a string of tubing, an upwardly opening valve at the lower end thereof, a sucker rod, a cup on said rod reciprocal in said tubing, upwardly directed means on said rod to hold said cup erect and

to allow it to collapse inwardly and means to flush said cup free of sand.

7. In a pump, a pump rod, an upwardly flaring cup of flexible material secured tightly to said rod, adjustable means on said rod to prevent undue expansion of said cup and adapted to allow the collapse of said cup on the downward stroke of the rod to permit the passage of fluid outside thereof, and additional means to flush said cup free of sand.

8. In a pump, a string of tubing, a pump rod reciprocable therein, an upwardly flaring cup secured to said pump rod, a valve controlled passage for fluid upwardly through said rod within said cup, and means to limit the outward movement of the upper end of said cup.

9. In a pump, a pump rod, a tubular section connected in said rod, an upwardly flaring cup of flexible material on said section, means adjustably connected with said rod to limit the downward movement of the

upper edges of said cup, and means to flush said cup free of sand. 25

10. In a pump, a pump rod, a tubular section thereon, a flexible cup on said section, said section having openings from below said cup to the interior of said cup, and supporting means for the upper edges of said cup. 30

11. In a pump, a pump rod, a tubular section thereon, a flexible frusto-conical shaped cup secured at its lower end tightly to said section, and adjustable supporting means 35 for said cup adapted to allow said cup to collapse on the downward stroke and support said cup on the upward stroke of the rod, said section being perforated to allow a limited discharge of fluid upwardly 40 through said cup for the purpose described.

In testimony whereof, I hereunto affix my signature, this the 19th day of October, A. D. 1920.

OSMYN MOWERS.
